UNITED STATES PATENT OFFICE.

HORACE FALK NEUMEYER, OF MACUNGIE, PENNSYLVANIA.

FLUSHING APPARATUS.

SPECIFICATION forming part of Letters Patent No. 743,184, dated November 3, 1903.

Application filed October 21, 1902. Serial No. 128,180. (No model.)

To all whom it may concern:

Be it known that I, HORACE FALK NEUMEYER, a citizen of the United States, residing at Macungie, in the county of Lehigh and State of Pennsylvania, have invented a new and useful Flushing Apparatus, of which the following is a specification.

The present invention relates to flushing apparatus for closets, and more particularly to that class in which the mechanism is operated by the depression of the seat.

One of the objects of this invention is to provide practical valve mechanism of an extremely simple character that is not liable to become leaky or inoperative and is so arranged that the parts may readily be reached, removed, and repaired or renewed by persons other than expert plumbers.

The preferred embodiment of the invention is fully illustrated in the accompanying drawings, wherein—

Figure 1 is a view in elevation of the apparatus when applied to a closet. Fig. 2 is a vertical sectional view, on an enlarged scale, through the mechanism. Fig. 3 is a transverse sectional view taken on the line *x* *x* of Fig. 2. Fig. 4 is a detail sectional view taken on the line *y* *y* of Fig. 3.

Similar numerals of reference denote corresponding parts in all the figures of the drawings.

In the embodiment shown a bowl 10 is employed, to which is connected the usual soil-pipe 11, said bowl having a hinged seat 12 arranged thereon. These parts may be of any desired construction and in themselves form no part of the present invention. Beneath the bowl is arranged a vault 13, within which the mechanism is housed.

Suitably supported within the vault 13 is the valve mechanism, which is constructed as follows: A body 14 is employed having a depending stem 15, which is attached, by means of a base 16, to a support 17, fastened to the soil-pipe. This body is provided with an interior chamber 18, at one end of which is arranged an inlet-opening 19, while the other end is provided with a discharge-opening 20, the portions of the body about these openings being formed into suitable valve-seats. A supply-pipe 21 is connected with the inlet end of the body by a suitable coupling 22, while a dis-

charge-conduit 23 is in like manner connected to the discharge end of the body. The top of the body is in the form of a threaded nipple 24, having an opening 25 therein, which opening communicates with the chamber 18. To this nipple is secured a pipe 26, the other end of which is attached to the lower end of a reservoir 27, arranged within the vault 13, as clearly shown in Fig. 1, said reservoir being air-tight. A valve-stem 28 is slidably mounted in the chamber 18 and has its ends projecting beyond the same, being provided with annular flanges 29 and threads, as 30. Upon these ends are arranged valves 31, constructed of rubber or other compressible material and held in place by flanged nuts 32. The valves are arranged to alternately close the inlet and outlet openings of the chamber 18 upon the movement of the stem 28. To secure this movement, an actuating-spindle 33 is journaled in the body and extends across the chamber between the valve-stem 28 and the upper opening 25, the inner end of the spindle being located in a seat 34, the other end projecting through a suitable journal-opening 35 and having a reduced outer terminal 36. In order to prevent leakage at this point, a packing-cap 37 is secured about the projecting end of the spindle. The valve-stem 28 is provided in an intermediate portion with a socket 38, and the actuating-spindle has a threaded opening 39 therethrough, said opening and socket being arranged to align with the upper opening 25 of the body. A connecting-finger 40 is threaded through the spindle and has its lower end engaging in the socket 38, as shown in Fig. 2. This finger is preferably provided with a tool-receiving slot 41 in its upper end, and thus by removing the pipe 26 access can be gained to the finger, so that it may be removed from the spindle through the upper opening 25 of the body. The outer reduced terminal of the spindle 33 is made angular, and to the same is attached a lever 42, one arm of which is longer than the other arm. Upon the long arm is slidably mounted a weight 43, normally held against movement by a set-screw, as 44. The other arm is provided in its upper edge with a notch, as 45, and a stirrup 46 is arranged upon this latter arm, said stirrup being provided with an opening to receive the same, the upper

wall of the opening tapering to a knife-edge, as 47. The stirrup is held in place by a split key 48, passed through the free end of the lever-arm. This stirrup is secured to the 5 lower end of an upright operating-rod 49, extending through a suitable guideway 50^a. formed on the bowl and constituting a support for the seat 12, which is normally held raised a slight distance from the upper edge 10 of the bowl by means of the weight 43, as will be readily understood. The discharge-conduit 23, connected with the discharge end of the body 14, is also attached to an upright coupling 50, and to the upper end of said 15 coupling is secured a conduit 51, leading to the upper end of the bowl. This coupling 50 has a reduced vent-opening 52 in its lower end, and a pipe 53, secured to said lower end, leads to the soil-pipe, as shown in Fig. 1. 20 The vent 52 is controlled by a plug or cone valve 54, arranged exteriorly of the coupling 50 and having a stem 55 passing through the vent, said stem carrying at its upper end a horizontal disk 56, that is arranged transversely of the passage-way. This disk under 25 normal conditions rests upon an annular shoulder 57, arranged within the coupling and having slots 58 through the same to permit the escape of water. A pressure-reducing disk 59 is secured across the channel, being interposed between the ends of the 30 pipe 51 and the coupling 50, said disk having an opening 60 therethrough that is of less diameter than the diameter of the passage-way. The upper end of the pipe 51 passes through the edge of the bowl, and to its inner end is secured a flushing-jet 61 in the form of a cap having in its end wall a transverse slot 62, the portion of the cap on one 35 side of said slot being inset, as shown at 63. The jet, furthermore, has openings 64 in its side walls. Under ordinary conditions the inlet 19 is closed by its valve, because of the arrangement of the weight 43, which likewise 40 elevates the seat 12 in the manner shown in Fig. 1. When said seat is depressed, the rod 49 will be forced downward, thus turning the actuating-spindle 33 and opening the inlet to the body, at the same time closing the outlet. 45 Water will therefore pass from the supply-pipe through the pipe 26 into the reservoir until the pressure of the air within the same equals the pressure of the water-supply. As soon as the seat is elevated the weight 43, acting 50 on the lever 42, will again close the inlet-valve and open the outlet, whereupon the air under pressure in the reservoir will force the water from said reservoir through the various conduits to and through the flushing-jet. 55 During its flow, however, it will strike the disk 56 and elevate the same, thereby moving the valve 54 to closed position and cutting off the vent. As soon as the flow of water has ceased the disk and valve will again drop, 60 whereupon the vent will be opened and the water remaining in the pipes and reservoir will gravitate through said vent and into the

soil-pipe, so that no standing water will remain in the apparatus.

It will be seen that the various elements of 70 which this apparatus is composed are extremely simple and that they may be readily reached for the purpose of repair or renewal. For instance, if it is desired to remove the valves and operating mechanism therefor it 75 is only necessary to uncouple the several pipes from the body, whereupon the screw-finger may be removed through the opening 25 while the valves are exposed. Attention is also invited to the construction of the connection 80 between the operating-rod 49 and the lever 42. This structure is of such a nature that it cannot readily become inoperative, and there is practically no friction between the 85 parts.

From the foregoing it is thought that the construction, operation, and many advantages of the herein-described invention will 90 be apparent to those skilled in the art without further description, and it will be understood that various changes in the size, shape, proportion, and minor details of construction may be resorted to without departing from the spirit or sacrificing any of the advantages of 95 the invention.

Having thus described my invention, what I claim as new, and desire to secure by Letters Patent, is—

1. In flushing apparatus, the combination with a chambered body having an opening in 100 one side, of a valve having a stem movable in the chamber of the body, an actuating device for the valve extending into the body between the opening thereof and the valve-stem, and a connection between the actuating device 105 and valve-stem, said connection being detachable from both the actuating device and stem and removable through the opening in the body.

2. In flushing apparatus, the combination with a chambered body, of a valve having a stem movable in the chamber of the body and provided with a socket, an actuating device for the valve extending into the body and having an opening therethrough, and a pin 115 detachably passed through said opening and engaging in the socket of the valve-stem.

3. In flushing apparatus, the combination with a chambered body, of a valve having a stem movable in the chamber of the body, an actuating device for the valve extending into the body and having a threaded opening therethrough, and a pin threaded through said opening and engaging in the socket of the valve-stem.

4. In flushing apparatus, the combination with a chambered body having an inlet, of a valve closing the inlet and having a stem 120 slideable in the chamber of the body, said valve being provided with a socket, an actuating-spindle for the valve journaled in the body and having a threaded opening therethrough, and a pin screwed through said opening and engaging in the socket of the valve-stem.

5. In flushing apparatus, the combination with a chambered body having an opening in one side, of a valve having a stem movably mounted in the chamber of the body and being provided with a socket, an actuating-spindle journaled in the body and having an opening arranged to aline with the socket and the opening in the body, and a connecting-finger passed through the spindle and engaging in the socket of the stem, said pin being removable through the opening in the body.

6. In flushing apparatus, the combination with a chambered body having an opening in one side, of a valve having a stem movable in the chamber of the body, an actuating device for the valve extending into the body, said stem and device having an opening and a socket arranged to aline with the opening of the body, and a connection between the valve and actuating device detachably fitted in the opening and socket thereof and removable therefrom when alined with the opening of the body.

7. In a flushing apparatus, the combination with a chambered body having an inlet and outlet and an intermediate opening, of a valve-

stem slidably mounted in the chamber of the body and having valves coacting with the inlet and outlet, said stem having a socket, a transverse actuating-spindle journaled in the body 30 between the valve-stem and the intermediate opening, and a finger detachably passed through the spindle and removable through the opening, said finger having the end opposite said opening projecting beyond the spindle and engaging in the socket of the valve-stem.

8. In flushing apparatus, the combination with a valve, of operating mechanism for the valve, said mechanism including a lever having a notch, and an actuating device comprising a stirrup that embraces the lever and has an inner tapering wall, the edge of which is arranged to bear against the lever during its movement and engage in the notch thereof. 40 45

In testimony that I claim the foregoing as my own I have hereto affixed my signature in the presence of two witnesses.
